UNITED STATES PATENT OFFICE.

WALTER E. BANNING, OF SYRACUSE, NEW YORK.

DESIGN FOR A STAMP-HOLDER.

SPECIFICATION forming part of Design No. 24,145, dated March 26, 1895.

Application filed May 7, 1894. Serial No. 510,427. Term of patent 3½ years.

To all whom it may concern:

Be it known that I, WALTER E. BANNING, a citizen of the United States, residing at Syracuse, in the county of Onondaga and State of New York, have invented and produced a new and original Design for a Rubber Stamp, of which the following is a specification, reference being had to the accompanying drawings, showing a part thereof.

10 My invention relates to a design for stamp-holders, and it consists in the ornamental configuration and shape shown in the drawings, and which will be more fully described hereinafter.

15 The object of my invention is to give the stampholder a novel and pleasing appearance.

Figure 1 is a perspective of a design which embodies my invention. Figs. 2 and 3 are respectively plan and inverted views of a 20 stamp holder embodying my invention.

The body of the stamp holder is oblong and has rounded ends. The top B is flat and has

a rim or flange f, extending entirely around its edge. Rising from the center of this top is the handle A, having the shape shown. The 25 under side of the body is flat. Extending up the sides of the body are the semi-cylindrical figures 1, separated an equal distance apart, and having tapering upper ends, as shown. The lower ends of these figures 1 form a scallop around the edge of the under side C of the holder, as shown in Fig. 3.

Having thus described my invention, I claim—

The design for a stamp holder, substantially as shown.

In testimony whereof I affix my signature, in presence of two witnesses, this 28th day of November, 1893.

WALTER E. BANNING. [L. S.]
